MEANS FOR SLITTING PLATFORM WRAPPERS

Napoleon S. Ferland, Beverly, Mass., assignor to United Shoe Machinery Corporation, Flemington, N. J., a corporation of New Jersey

Application February 5, 1953, Serial No. 335,201

7 Claims. (Cl. 12—1)

This invention relates to means for slitting portions of shoe uppers and is herein illustrated as embodied in a device for slitting the margin of a platform wrapper in order to facilitate the subsequent disposition of the wrapper. It is to be understood, however, that in various novel aspects the invention is not limited to the illustrative embodiment thereof.

It is an object of the present invention to provide a simple and conveniently operated device which may be mounted adjacent to an upper shaping machine and manually operated by the operator of the machine to slit the free margin of the platform wrapper in order to facilitate the shaping operation.

With the above object in view the invention in one aspect thereof comprises a stationary cutter having a fixed cutting station, a shoe carrier constructed and arranged to support the forepart of a shoe in upright position, and means herein illustrated as a bench fixture mounting the carrier for movement lengthwise of a shoe thereon relatively to the cutter. In the illustrated organization the fixture provides a mounting for both the cutter and the carrier. The carrier is preferably slidably mounted on the fixture for a movement of translation relatively to the cutter. When there is no shoe on the carrier, a detent mounted in the fixture holds the carrier against movement relatively to the cutter so that the carrier provides a shield which prevents accidental contact of the fingers of the operator with the cutter, the detent being characterized by an extension constructed and arranged to be engaged by a shoe as it is mounted in the carrier thereby to displace the detent from its operative position in order to permit movement of the carrier relatively to the fixture. In the illustrated organization the carrier is so constructed and arranged that one edge thereof is engaged by the inner surface of the free margin of the platform wrapper of a shoe positioned on the carrier and thus the carrier is advanced with the shoe by manual movement of the shoe toward the operator. Such a movement of the shoe transfers the shoe in a path such that a portion of the margin of the platform wrapper passes through the station occupied by the cutting edge of the cutter and is slit thereby.

In the illustrated organization a plurality of cutting blades are attached to the fixture and have their cutting edges disposed in planes extending heightwise of a shoe on the carrier so that a plurality of slits are cut substantially concomitantly in the margin of the platform wrapper during the movement of the shoe.

The invention will now be described with reference to the accompanying drawings and pointed out in the appended claims.

In the drawings,

Fig. 1 is a side elevation of a cutting means embodying the features of the present invention, the toe portion of a shoe being shown mounted on the work supporting carrier of the cutting means;

Fig. 2 is a longitudinal section through the center of the cutting means and the toe portion of a shoe mounted

2

thereon; the shoe and the work support being shown in the position which they occupy upon the completion of the cutting operation.

Fig. 3 is a plan view with a portion of the work supporting carrier broken away to show the mounting of certain of the cutting blades; and

Fig. 4 is a section on the line IV—IV of Fig. 3.

For mounting the illustrated mechanism an inverted U-shaped bracket 10 is secured to the top of a bench 12 by bolts 14 and arranged to extend vertically upwardly therefrom; the front of the bench 12 being to the left as seen in Fig. 1. A fixture herein illustrated as a plate 16 is rigidly secured by headed screws 18 to the horizontal portion of the bracket 10 and is arranged to extend to the right from the bracket as seen in Fig. 1.

At its right end portion, as seen in Fig. 3, the fixture 16 is recessed at 19 to provide therein a plane vertical surface coincident with the longitudinal center line of the fixture. A central cutting blade 20 is located against said surface and is secured thereto by a headed clamping screw 22 which, as shown in Fig. 2, extends through an open-ended slot 24 in the left end portion of the cutting blade. The square end portion of the cutting blade is seated against the base of a narrow groove formed in the fixture 16 in order to cause the blade to be rigidly retained in the fixture and to be securely held against angular movement. To provide for the mounting of two cutting blades 26 the fixture is recessed at opposite sides thereof to provide plane vertical surfaces parallel to the longitudinal center line of the fixture for the mounting of two cutting blades 26. The blades 26 are seated in narrow grooves in the fixture similar to the groove provided for the blade 20 and are secured against the vertical surfaces above referred to by clamping screws 28 extending through open-ended slots (not shown) in the cutting blades. As shown in Fig. 3, the central cutting blade 20 is offset to the right from the blades 26 which are located directly opposite each other so that the three blades will operate substantially concomitantly on the margin of a platform wrapper at one end of a shoe.

For supporting the forepart of a shoe in upright position, as shown in Figs. 1 and 2, a carrier herein illustrated as a plate 30, is slidably mounted on the fixture 16 and its opposite marginal portions (Fig. 4) are bent to form channel sections 32 which embrace the reduced marginal portions 34 at opposite sides of the fixture 16. These marginal portions serve to guide the carrier plate 30 for movement in a rectilinear path extending longitudinally of the fixture 16 and they also serve to hold the carrier plate against vertical movement relatively to the fixture. The right end portion 35 of the carrier plate, as shown in Fig. 3 is symmetrically curved to form a contour corresponding generally to the edge contour at the toe portion of a shoe. The carrier plate 30 is urged toewardly or to the right, as seen in Figs. 2 and 3, by a tension spring 36 mounted in a cylindrical groove 38 formed in the fixture 16 and extending from the left end of the plate as seen in Fig. 3 to its central portion along the longitudinal center line of the fixture. As shown in Fig. 2, the left end of the spring 36 is anchored to a pin 40 mounted in and projecting downwardly from the carrier plate 30, and the right end of the spring is anchored to the reduced upper end portion of a headed screw 42 mounted in the bottom of the fixture 16 and projecting upwardly through the groove 38. The spring 36 normally holds the carrier plate 30 at the limit of its movement to the right, as shown in Fig. 3, in a position determined by the engagement of the head 44 of a detent in the circular portion of a keyhole slot 46 formed in the carrier plate 30 and extending longitudinally thereof midway between its opposite side portions. Referring to Fig. 2, the head 44 of the detent is cylindrical

in shape and has an annular flange 48 at its base the edge face of which is arranged for sliding engagement with the cylindrical surface of a vertical bore 50 in an externally threaded member 52 seated in a tapped bore in the fixture 16. The detent is urged upwardly by a spring 54 surrounding a stem 56 extending downwardly from the head of the detent through a bore in the base 58 of the member 52, the spring being confined between the base 58 and the head of the detent. The head of the detent is moved downwardly out of the circular portion of the keyhole slot by the engagement of the sole of a shoe with the upper extremity of a stem 60 extending upwardly from the head 44 of the detent, said stem being slightly less in diameter than the width of the narrow portion of the keyhole slot.

In the operation of the illustrated cutting means the forepart of a shoe is arranged in upright position and mounted on the carrier plate 30, as shown in Fig. 1. The illustrated shoe comprises an upper 62 stitched to a sock lining 64 (Fig. 2) to which there is also stitched a wrapper 66 covering the edge face of a platform 68 cement attached to the sock lining. A last 70 has been inserted into the shoe in accordance with the usual practice in the manufacture of slip lasted footwear. The shoe is so located on the carrier plate 30 that the inner surface of the downwardly projecting margin of the platform wrapper 66 at one end of the shoe is arranged in contiguous relation to the edge portion 35 (Fig. 3) of the carrier plate, said edge portion having a contour generally similar to the peripheral contour of an end portion of the platform 68. In mounting the shoe on the carrier the bottom surface of the platform 68 engages the upper end portion of the stem 60 and forces the detent downwardly against the pressure of the spring 54 displacing the head 44 of the detent from the circular portion of the keyhole slot 46 and leaving the carrier free to move to the left as seen in Figs. 1 to 3. After mounting the shoe on the carrier plate 30 the operator moves the shoe endwise, or to the left, as seen in Fig. 1, the carrier plate moving with the shoe by reason of the engagement of the platform wrapper therewith. It will be seen that the movement of the shoe from its position in Fig. 1 into its position illustrated in Fig. 2, causes the cutters 20 and 26 to cut open-ended slits in the downwardly projecting margin of the platform wrapper. After the movement of the shoe with the carrier plate 30 has been terminated by the engagement of the small end of the keyhole slot with the stem 60, the operator lifts the shoe from the carrier plate and the spring 36 returns the carrier plate to its rest position illustrated in Fig. 3, 50 whereupon the spring 54 moves the detent upwardly into its locking position.

Having thus described my invention, what I claim as new and desire to secure by Letters Patent of the United States is:

1. The combination comprising a stationary cutter having a fixed cutting station, a shoe carrier constructed and arranged to support the forepart of a shoe in upright

position, and means mounting the carrier for movement lengthwise of a shoe thereon relatively to the cutter.

2. The combination comprising a stationary cutting blade, a generally sole shaped shoe carrier constructed and arranged to support the forepart of a shoe in upright position, and a fixture in which the cutting blade is rigidly mounted and on which the carrier is slidably mounted for movement relatively to the cutting blade.

3. The combination comprising a cutter, a fixture to which the cutter is attached, a shoe carrier mounted on the fixture for a movement of translation relatively to the cutter, and a detent mounted in the fixture and constructed and arranged to hold the carrier against movement relatively to the cutter, said detent being characterized by an extension constructed and arranged to be engaged by a shoe as it is mounted on the carrier thereby to displace the detent from its operative position.

4. The combination comprising a shoe carrier, a plurality of cutting blades having a common orientation and having their cutting edges disposed in planes extending heightwise of a shoe on the carrier, and means mounting the carrier for movement relatively to the cutting blades.

5. The combination comprising a stationary slitting cutter having a fixed cutting station, a shoe carrier comprising a plate constructed and arranged to support the forepart only of a shoe in upright position, said carrier plate having an edge contoured to engage a platform wrapper depending from a shoe on the carrier, and means mounting the carrier for movement relatively to the cutter.

6. The combination comprising a shoe carrier, a plurality of cutting blades constructed and arranged to form open-ended slits in the margin of a platform wrapper depending from a shoe on the carrier, and means mounting the carrier for movement relatively to the cutting blades.

7. The combination comprising a stationary cutting blade having a fixed cutting station, a shield for the blade, means mounting the shield for sliding movement to expose the blade, and means for returning the shield to its shielding position, said shield being constructed and arranged to support the forepart of a shoe by its bottom surface with a platform wrapper depending from the shoe in substantially contiguous relation to an edge of the shield.
